UNITED STATES PATENT OFFICE.

GEORGE F. REINHARDT, OF NEWTON, MASSACHUSETTS.

DESIGN FOR A CONNECTED PAIR OF HALF-SOLES.

60,264.

Specification for Design.

Patented Jan. 17, 1922.

Application filed June 16, 1920. Serial No. 389,494. Term of patent 14 years.

To all whom it may concern:

Be it known that I, GEORGE F. REINHARDT, a citizen of the United States, residing at Newton, in the county of Middlesex and Commonwealth of Massachusetts, have invented a new, original, and ornamental Design for a Connected Pair of Half-Soles, of which the following is a specification, reference being had to the accompanying drawing, forming a part thereof.

In the drawings:

Fig. 1 is a perspective view of a connected pair of half soles, showing my new design.

Fig. 2 is a plan view.

The leading features of the design consist in the symmetrical form of the parts on each side of the transverse median line, the convexity of one longitudinal edge, and the concavity of the middle part of the opposite longitudinal edge.

I declare that what I claim is:

The ornamental design for a connected pair of half soles as herein shown and described.

GEORGE F. REINHARDT.
